UNITED STATES PATENT OFFICE.

MARY L. BUCKLEY, OF NORTH ATTLEBORO, MASSACHUSETTS.

TEMPLATE AND METHOD OF FABRICATING ORNAMENTS THEREWITH.

Application filed October 27, 1921. Serial No. 510,810.

To all whom it may concern:

Be it known that I, MARY L. BUCKLEY, a citizen of the United States, residing at North Attleboro, in the county of Bristol and State of Massachusetts, have invented 5 certain new and useful Improvements in Templates and Methods of Fabricating Ornaments Therewith, of which the following is a specification.

10 My invention relates to a means for fabricating flowers and other ornaments from worsted, yarns, and the like.

The essential objects of my invention are speed and simplicity in construction of the 15 ornaments and capacity for variety in visual effect of the same; together with inexpensiveness of the means and method of fabrication.

To the above ends essentially my invention consists in such parts and in such combinations of parts, and in such steps and in such successions of steps as fall within the scope of the appended claims.

In the accompanying drawings which 25 form a part of this specification,

Figure 1 is a perspective view of a template employed in my invention,

Figures 2 and 3, a front and rear elevation respectively of the same, showing the 30 flexible member in an initial stage of manipulation,

Figure 4, a front elevation of the template showing the ornament at the completion of the winding operation,

35 Figure 5, a similar elevation of the ornament immediately after disengagement from the template, and

Figure 6, a perspective view of a completed ornament.

40 Like reference characters indicate like parts throughout the views.

In detail my invention comprises a template or disk 8 of thin stiff material such as cardboard, but preferably of metal, of 45 generally circular outline and provided with a central hole 9. Preferably but not essentially a prong or hook 10 is struck up from the material at a point adjacent the hole and covers the resultant opening 11. The 50 periphery of the disk or template consists of a series of resultant elevations 13 caused by peripheral equispaced notches 14, in this instance eight in number. It is in conjunction with a planchet of this general character 55 that the ornament is preferably constructed.

The fabrication of the ornament is as follows. A flexible strand 16 of yarn or other soft material has one end 17 threaded in a sewing needle 18, and its other end 20 60 pressed by the operator's finger against the back of the template, or held thereby by the prong 10 when such a prong is present. The needle is first passed through the hole from rear to front, and the strand is then manually 65 passed by one hand through one notch 14 as at *a*, thence behind an elevation 13 to the next adjacent notch, as at *b*, forming a loop 22, and thence is passed diametrically across the front of the template as at *c*. 70 This operation is repeatedly continued, the strand passing successively through the notches as at *d*, *e*, *f*, *g* and *h*. During the described winding the thumb of the operator's other hand pinches the intermediate 75 portions of the strands against the face of the plate until they are caught together by passing the needle and strand from the notch, as at *h*, to points behind the pressed portions of the strands as shown in Figure 80 2, and there brought around to unite at a single central point the radially disposed portions or arms 23 of the strand.

The planchet is next intermittently turned by one hand while the strand 16 is 85 wound with the assistance of the needle 18 around each successive arm 23 forming loops 25 thereon connected by parallel connecting portions or layers 26 extending from the center of the template to its margin, as 90 shown in Figure 4.

The fabric ornament thus far completed is now removed from the template by stretching the loops 22 out of engagement with the portions 13, and while in the position shown in Figure 5 the thread or strand 16 is passed through all of the peripheral loops 22, and is then tightened somewhat which causes the fabric or body 28 to fold rearwardly upon itself and form a convexo 100 concave or flower shaped ornament, as shown in Figure 6. It is usual after completion of the ornament to tie the adjacent ends 17 and 20 of the thread 16 into a knot 30.

It will be understood that the curved 105 shape of the elevations 13 is not exclusive as the same may be angular or otherwise if desired, but superior advantages are inherent in a nonangular form.

I claim:—

1. A template of the character described, comprising a flat disk provided with a cen-

tral hole and yarn-retaining means adjacent thereto, and provided with a plurality of spaced peripheral cavities.

2. A template of the character described, comprising a disk provided with a central hole, and with a series of peripheral cavities, and a prong integral with the disk adjacent the hole.

3. A method of fabricating ornaments consisting of arranging a flexible member so

as to form radial arm portions terminating in loops connecting the arm portions, then passing the flexible member around the arm portions in succession from their inner ends to the loops to form a body, then threading 15 the flexible member through the loops and tightening the member.

In testimony whereof I have affixed my signature.

MARY L. BUCKLEY.
